METHOD OF MAKING RING TRAVELEES

Eric Gilbert Peterson, Riverside, R. I., assignor to
 Victor Ring Traveler Company, a corporation of
 Rhode Island

Application July 19, 1935, Serial No. 32,266
 Renewed July 25, 1939

7 Claims.

(Cl. 29—171)

This invention relates to a ring traveler, and has for one of its objects the shaping of the wire which forms the traveler such that there will be provided a longer wearing life for the traveler.

Another object of the invention is to provide a traveler which by reason of the shape of its wire will have less friction and provide a cooler running traveler and one which may be thicker and thus wear longer than those heretofore provided.

Another object of the invention is the provision of a traveler which will minimize breakage caused by a progressive fracture or sometimes called "fatigue" by stiffening and strengthening the bends.

Another object of the invention is to lessen through rearrangement and without heating the strains of tension and compression in the stock of the traveler about the bends which sometimes cause a progressive fracture to occur.

With these and other objects in view, the invention consists of certain novel features of construction, as will be more fully described, and particularly pointed out in the appended claims.

In the accompanying drawing:

Fig. 1 is a perspective view of a traveler of an enlarged size after it has been taken from the forming tool;

Figs. 2 to 8, inclusive, show this traveler after being deformed in different portions along the length of the wire each one being a modification with reference to the other;

Fig. 9 is a perspective view of a length of wire from which the traveler is formed.

After a traveler has been formed up by a bending of the wire, one of the conventional forms of relieving strain in the traveler is to apply a low temperature heat treatment, which treatment serves to relieve to some extent the strains of tension and compression. However, instead of this heat treatment, I relieve the strains of tension and compression by deforming the stock of the wire whereby the strains are substantially eliminated in the finished traveler; and the following is a more detailed description of the present steps in the operation of the formation of my traveler by which I attain the desired results:

In the formation of travelers, the same are frequently made from a piece of round wire stock which has been flattened by pressure on diametrically opposite points forming somewhat of an oblong cross-section, as shown in Figure 9,

with flat surfaces 28. The wire of this cross-section is bent in a cold condition about a forming tool with the flat surfaces parallel to the axes of the arcs of bending to provide a shaping of the wire which will fit about the opposite edges of the ring and provide a space to allow yarn to pass through the traveler for the proper control thereof.

The bends which are necessary in the wire form curvatures which are rather sharp and cause the metal or wire to be placed under tension strains at the outside or periphery of the bends, as designated at 10 and 11 in Figure 1, where the metal is stretched or tended to be pulled apart, while there are compression strains at 12 and 13 in Figure 1 on the inner or underside of the bend where the metal has been compressed or crimped due to bending. The bends of this sort which cause the metal to be placed under these strains of tension and compression also affect the hardness, for instance according to the Rockwell standard of hardness, whereas as the shank originally has a hardness of 82 along the central or neutral axis, and 83 on the outer surface or edge as designated by these corresponding numerals in Figure 1, it will be found that along the bend at the neutral axis the hardness will be 83, 83.5, 86 and 85.5 at the corresponding locations which the lead lines of 25 these numbers designate in Figure 1, while on the outer surface the hardness will be found to be 90 and on the inner surface 91 at the point of greatest curvature, whereas at the tips of the wire it will be 86, as indicated. The bending 30 of the wire around the former causes the metal to be placed under additional tension and compression strains in the bends, materially increasing the surface hardness of the bends although only slightly affecting the central or neutral axis.

If the traveler is left as bent with the strains of tension and compression in the metal, although the traveler as a whole is capable of 35 withstanding the forces under which it is put, it will be found that where the traveler is subjected to strains or stresses in opposite directions or in different directions that the material will after a time fatigue, that is, small cracks will start in the surface, and as the vibrations and alternate opposite strains occur such as may occur in the traveler due to rough rings, uneven tension from knots in the yarn or the like, that these small cracks will penetrate deeper and deeper through the stock of the wire until finally there remains an insufficient cross-section of the

wire to withstand the strain to which the traveler is subjected, whereupon the traveler breaks. The characteristic of the line of break is such that there is usually a smooth portion of the cross-sectional area where the crack has been penetrating gradually into the wire and which has become worn smooth by reason of the relative smoothness of the parts to break off the roughness of the grain structure of the metal, and finally when there remains insufficient cross-sectional area to support the forces existing, a clean break will occur in which the break area is rough and unpolished. This is usually known as fatigue, and a break of this character has been found to occur more largely where alterations of stresses and strains of compression and tension exist.

In order that the strains of compression and tension in the wire may be relieved or rearranged to a large extent I have deformed the wire by a striking, rolling or hammering operation to flatten portions of it such as shown at 15 and 16 in Figure 2 at the curved portions thereof, which flattening serves to rearrange the strains of tension and compression so that the alternating or vibrating strains such as occur in operation on poor, rough rings or due to dry spots or the like or uneven tension will not cause the traveler to fail or have a progressive break as quickly as would occur if the strains were not so rearranged.

The deformity or flattening which I provide is in a direction parallel to the axis about which bending occurs and serves to thicken the stock of the traveler or increase its dimension at right angles to a tangent to the surface of the ring against which it wears to such an extent that the thickness is often greater in the area of wear than the original thickness of the traveler so that although there is a reduced amount of surface area for contacting with the ring with respect to the usual construction, its depth is greater and its wearing life is longer both by reason of the action of the thread and the ring, and further, by reason of this flattening or thinning out of the traveler in this dimension a greater wind area is provided effecting faster heat dissipation resulting in a cooler and longer wearing life of the traveler than would otherwise occur which is highly desirable.

While I have shown in Figure 2 a flattening occurring at the opposite ends of the top and bottom of a traveler of a vertical type, this flattening may occur only at the top as shown at 15 in Figure 3, or it may occur at the top and along the shank as shown at 15 and 17 in Figure 4, or merely at the bottom as shown at 16 in Figure 5, or along the shank only as shown at 17 in Fig-

ure 6, or along the shank and bottom as shown at 17, 18 in Figure 7, or it may occur along the entire length of the wire as shown at 15, 17, 18 in Figure 8. Thus, the strains caused by flat rolling of the wire and the additional strains put in by bending are relieved and rearranged. This change also affects all of the physical properties of the metal, there being a change of tensile strength wear resistance, etc.

10 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. The method of forming a traveler from a length of wire, comprising bending the wire to the desired shape and then deforming the cross-section of the wire to relieve or rearrange some of the strains placed therein by bending.

20 2. The method of forming a traveler from a length of wire, comprising bending the wire to the desired shape and then deforming the cross-section of the wire along the bent portion to relieve or rearrange some of the strains placed therein by bending.

25 3. The method of forming a traveler from a length of wire, comprising bending the wire to the desired shape and then flattening the cross-section of the wire to relieve or rearrange some of the strains placed therein by bending.

30 4. The method of forming a traveler from a length of wire, comprising bending the wire to the desired shape and then flattening the cross-section of the wire by hammering to relieve or rearrange some of the strains placed therein by bending.

35 5. The method of forming a traveler from a length of wire, comprising bending the wire to the desired shape and then flattening by pressure applied in a direction at right angles to the axis of the bending.

40 6. The method of forming a traveler from a length of wire, comprising bending the wire to the desired shape and then deforming the cross-section of the wire by force applied at right angles to the axis of bending.

45 7. The method of forming a traveler from a length of wire, which consists in flattening the wire to provide a width greater than its thickness, bending the wire about an axis generally parallel to the width dimension to the desired shape traveler, and then applying pressure in a direction to increase the thickness and decrease the width of the wire.
